BY *J. D. Ammen*
Atto ATTORNEY.

UNITED STATES PATENT OFFICE.

HENRY W. BOGART, OF CLEVELAND, OHIO.

FRUIT-JAR HOLDER.

SPECIFICATION forming part of Letters Patent No. 723,980, dated March 31, 1903.

Application filed March 27, 1902. Serial No. 100,244. (No model.)

To all whom it may concern:

Be it known that I, HENRY W. BOGART, a citizen of the United States, residing at Cleveland, in the county of Cuyahoga and State of Ohio, have invented certain new and useful Improvements in Fruit-Jar Holders, of which the following is a specification, reference being had therein to the accompanying drawings.

10 In placing the tops on fruit-jars or similar receptacles it is necessary to hold the jar while the cover is being placed upon it. This is often inconvenient, because the jar is frequently quite hot from the preserves which 15 have been poured into it, and for this reason a device which would not necessitate the operator's placing his hands upon the jar would be desirable. Devices have been produced for this purpose comprising an encircling 20 band with a handle; but they usually depend upon the movement of the handle to tighten the band, a mode of operation which has its disadvantages. Many of these devices, too, are adapted to only one size of jar or can be 25 applied to different sizes only within very narrow limits.

The object of this invention is to provide a device of the general class described which shall be adapted to operate upon jars of different sizes with the same efficiency and to so 30 construct the device that the tightening of the encircling band is in no way dependent upon the movement of the operating-handle.

A further object is to adapt the handle and 35 the method of its attachment to the band so that a force acting on the handle has a tendency simply to twist the device without distorting the band or changing the substantial uniformity of its pressure about the periphery of the jar.

The invention consists in a certain combination and construction of parts to be more fully described hereinafter and definitely set forth in the claims.

40 In the drawings which fully illustrate my invention, Figure 1 represents the same in perspective. Fig. 2 represents a portion of the device in perspective.

Referring to the parts by letters, A represents a band, preferably made of a flexible strip of metal, such as soft steel or brass. Its

inner portion is shaped substantially in the arc of a circle and is preferably provided, as indicated, with an outward offset *a*, wherefore shoulders *a'* are produced, between 55 which is mounted an elastic shoe or grip B. This grip is preferably formed of rubber and is adapted to project slightly into the space surrounded by the band. It is preferably scored or roughened upon its inner face *b* for 60 a purpose which will appear.

An operating-handle C, preferably made of pressed steel, which comprises forks or branches *c* *c'*, is provided and formed substantially as shown. Near their upper end 65 these forks bend outwardly, as shown at *c*², and beyond this point they bend inwardly again, as shown, respectively, at *c*³ and *c*⁴. The direction of these portions *c*³ *c*⁴ is such that they may be attached substantially tangentially to the aforesaid band A. The portion *c*⁴, however, is provided with an inward offset portion *c*⁵, by which it is attached to the inner extremity of the band and forming a shoulder *c*⁶. Extending back from this shoulder the portion *c*⁴ is provided with an offset portion *c*⁷, which is substantially in the same plane as the portion *c*⁵ and is integral with the handle. This portion *c*⁷, as indicated in Fig. 2, is pressed out of the portion *c*⁴, so 80 that the recess or guide *c*⁸ is formed, in which is guided a longitudinally-movable draw-bar D. This draw-bar is provided near its inner extremity with an outwardly-projecting pin *d*, which projects through a slot *e*, formed in 85 the band A, a small tightening-lever E. This lever is pivoted to the portion *c*⁴ at the point *e'*. The slot *e* is curved substantially in the arc of a circle and eccentric to the pivot-point *e'*, so that if this lever be depressed at *e'* the draw-bar D will be drawn inward by the eccentricity of the aforesaid slot *e*. The extremity of the draw-bar D is provided with an upwardly-extending tip *d'* for a purpose which will appear. 95

In operating the device the band is placed around the jar so that the rubber grip B rests against its side and one of the holes *a*² is made to engage with the aforesaid tip *d'*. The lever E then being operated and moved 100 to the depressed position, the withdrawal or inward movement of the draw-bar D causes

the band to be tightened securely about the jar. There is, however, a certain elasticity about the manner in which the band grasps the jar, due to the presence of the rubber grip or shoe B, which it will be remembered projects inward beyond the inner face of the band. The arrangement of the slot e with respect to the pivot of the lever is such that it maintains its position wherever placed.

10 After the operation outlined above has been completed the jar is ready to be filled and to receive its cover, and the handle C affords means for effectually preventing any rotation of the jar when the cover is being placed

15 upon it.

While the device described is expected to be most useful as a means for holding the jar itself when the cover is being removed or replaced, it is evidently equally well adapted for attaching itself to the cover, and where it is necessary to use considerable force in screwing the cover into place two devices of this kind can be used, or one of these can be used in connection with any of the forms 25 of fruit-jar wrenches commonly used for a similar purpose, but which operate upon the cover.

As there are a plurality of the openings a^2 , the device will evidently adapt itself to jars of 30 different sizes, which is most advantageous.

What I claim is—

1. In a device of the class described, in combination, a band of flexible material adapted to encircle a receptacle, a handle secured thereto, a draw-bar movable longitudinally with respect to said band, means whereby said draw-bar and said band may engage, and means for moving said draw-bar, substantially as set forth.

40 2. In a device of the class described, in combination, a band of flexible material adapted to encircle a receptacle, a handle secured thereto, a draw-bar movable longitudinally with respect to said band, said draw-bar having a projection, and said band having openings adapted to receive said projections, and a lever adapted to move said draw-bar with respect to said band, substantially as set forth.

3. In a device of the class described in combination, a band of flexible material adapted to encircle a receptacle, a handle having forks attached thereto, one of said forks having a longitudinal guide therein, a member movably mounted within said guide, a lever adapted to move said member within said guide, said member having a projection at its tip and said band having openings near its extremity adapted to receive said projection, substantially as set forth.

60 4. In a device of the class described, in combination, a band of flexible material adapted to encircle a receptacle, a handle having diverging forks attached to said band, a draw-bar, means for guiding the same longitudinally with respect to said band, a lever having an opening eccentric with respect to the pivot thereof, a member carried by said draw-

bar and lying within said opening and means whereby said draw-bar may engage said band, substantially as set forth.

70 5. In a device of the class described, in combination, a flexible band adapted to encircle an object, a draw-bar, means for guiding the same, means whereby said draw-bar may engage said band, and a lever having a slot inclined with respect to its pivot-point, wherefore a movement of said lever may move said draw-bar, substantially as set forth.

75 6. In a device of the class described, in combination, a flexible band adapted to encircle a receptacle, a draw-bar, means for guiding the same longitudinally with respect to said band, a lever having an opening eccentric with respect to the pivot thereof, means whereby said opening may engage said draw-bar and means whereby said draw-bar may engage said band, substantially as set forth.

80 7. In a device of the class described, in combination, a flexible band, a handle having forks, one of said forks having an offset portion wherefore a guide is formed within it, a member movably carried in said guide, means whereby said member may engage said band, and a lever controlling the movement of said movable member, substantially as set forth.

85 9. In a device of the class described, in combination, a flexible band, a handle having forks attached substantially tangentially to said band, a grip of elastic material carried on the inner face of said band, one of said forks having an offset portion wherefore a guide is formed within the same, a movable member mounted within said guide, said member having an outward projection, said band having openings adapted to engage with 100 said projection, a lever pivoted to said handle and connected with said member wherefore a depression of said lever may move the same, substantially as set forth.

10 10. In a device of the class described, in combination, a flexible metallic band adapted to encircle a receptacle, a handle having forks attached to said band at substantially opposite points, a grip of elastic material carried by the inner face of said band between the 105 points of attachment of said handle, a draw-bar, means for longitudinally guiding the same upon one of said forks, said draw-bar having an outer projection, said band having a plurality of openings which may engage 110 with said projection, a lever pivoted to one of said forks and having an opening eccentric with respect to said pivot, and a fixed pin carried by said draw-bar and passing through said opening, substantially as set forth.

115 11. In a device of the class described, in combination, a flexible metallic band adapted to encircle a receptacle, a handle having forks, one of which is attached to said band at one extremity thereof, the other of said forks being attached at a point substantially opposite, a grip of elastic material carried by the inner face of said band, between the point of attachment of said forks, a longitudinal

opening formed within one of said forks and constituting a guide, a draw-bar movably mounted therein, a lever pivoted to said fork, adjacent to said draw-bar and having an opening eccentric with respect to the pivot thereof, a fixed pin carried by said draw-bar and passing through said opening near the other extremity thereof, said draw-bar having a projection adapted to engage any of said openings, the pivot-point of said lever being in substantial alinement with the direction of

movement of said draw-bar, wherefore said parts may maintain themselves in a locked position when said band has been tightened about the receptacle, substantially as set forth.

In testimony whereof I affix my signature in presence of two witnesses.

HENRY W. BOGART.
